UNITED STATES PATENT OFFICE.

ALBERT F. PRIESTLEY, OF PHILADELPHIA, PENNSYLVANIA, ASSIGNOR TO HIMSELF AND BERNARD WIENERS, COPARTNERS, TRADING AS CAMDEN CITY CUT GLASS CO., OF CAMDEN, NEW JERSEY.

DESIGN FOR ORNAMENTATION FOR A CUT-GLASS ARTICLE OF MANUFACTURE.

59,681.

Specification for Design.

Patented Nov. 15, 1921.

Application filed April 13, 1921. Serial No. 461,108. Term of patent 7 years.

To all whom it may concern:

Be it known that I, ALBERT F. PRIESTLEY, a citizen of the United States, residing at Philadelphia, in the county of Philadelphia and State of Pennsylvania, have invented a new, original, and ornamental Design for Ornamentation for a Cut-Glass Article of Manufacture, of which the following is a specification, reference being had to the accompanying drawing, forming part thereof.

The drawing represents a face view of a portion of a cut glass article having my new design cut therein.

I claim:

The ornamental design for ornamentation for a cut glass article of manufacture, as shown.

In testimony whereof I affix my signature hereto.

ALBERT F. PRIESTLEY.
